METAL WORKING

John Karmazin, Sr., Grosse Ile, Mich.

Application April 27, 1953, Serial No. 351,279

3 Claims. (Cl. 113—38)

This invention relates to metal working and more particularly to a machine for use in manufacturing heat exchangers of the fin and tube type wherein a stack of superposed fin elements having integral tapered tubular projections are arranged in telescopic relationship.

It is an object of this invention to provide a die for manufacturing heat exchangers in which a strip of sheet metal is progressively reformed to provide rows of tubular portions without thinning or weakening the material forming the tubular portions beyond the desired strength requirements.

The invention represents an improvement over the method and machine shown in my prior Patent No. 1,669,761.

One of the big problems in manufacturing heat exchangers of the type disclosed herein is that of forming the tapered tubular projections on the fin elements so as not to unduly weaken the metal in the tubular projections.

In machines of the type previously used, the successive dies which were used in forming the tubular projections had their side walls arranged at progressively steeper angles. This has been clearly illustrated in Figure 7 in my United States Letters Patent No. 1,669,761. The use of progressively steeper dies results in rapid deterioration of the dies. Some of the larger manufacturers of heat exchange units have found it necessary to discontinue the use of tubular projections struck out from a piece of sheet metal, for the reason that the tooling costs made the cost of the heat exchange units too high, as compared with the cost of pipes projected through apertures in sheet metal fins. By arranging the dies at progressively increasing angles, any variation in the thickness of the sheet metal results in some of the dies near one end of the die assembly absorbing practically all of the impact of the punch press and the other dies absorbing practically none. If, for example, the thickness of the stock metal is increased, the dies at one end of the gang of dies absorbs practically all of the impact. On the other hand, if the thickness of the metal is decreased, the dies in the opposite end absorb practically all of the impact. The dies receiving the greatest impact fail, resulting in the necessity of replacing portions of the dies, realigning these replaced portions, et cetera. Moreover, the stock is overstressed, weakened and frequently ruptured by the overloaded dies.

It is thus a further object of this invention to provide a progressive die on which a succession of sets of tapered male and female die members have a uniform taper angle, whereby impact forces of the series are more uniformly distributed over the individual die sets, with changes in thickness of stock being worked upon, whereby wear on the individual sets is reduced, and the stock is not ruptured or weakened in the forming process.

Other objects and advantages reside in the construction of parts, the combination thereof and the mode of operation, as will become more apparent from the following description.

In the drawing:

2

Figure 1 is a plan view showing a plurality of fin strips in the process of manufacture;

Figure 2 is a sectional view taken substantially along the center line of one of the fin strips shown in Figure 1;

Figure 3 is a vertical sectional view showing the construction and arrangement of the successive dies used in forming tubular projections on the fin strips;

Figure 4 is a plan view showing a pair of fin strips having circular tubular projections in the process of manufacture; and

Figure 5 is a fragmentary elevational view showing a section of heat exchanger manufacture in accordance with my invention.

Referring now to the drawing, reference numeral 10 designates a thin sheet metal strip in the process of manufacture into a heat exchanger. As the strip 10 passes through the punch press, it is slit or precut into two or more strips as indicated by the parallel lines 12, so as to form a plurality of fin strips 14 having integrally formed tubular projections 16.

For purposes of illustrating the invention, there is shown in Figure 3 of the drawing one set of successive dies which is used in progressively forming the integral projections on a single fin strip, whereas there are six sets of these dies arranged side by side so as to make it

possible to form six separate fin strips, if desired, or to form six rows of tubular projections on a single fin strip. For purposes of illustrating the invention, there has been shown in Figure 1 of the drawing an arrangement in which a single wide strip of sheet metal is slit into six narrower strips, whereas certain aspects of the invention are equally applicable to an arrangement in which a lesser number of slits are made in the strip. Thus, one could, for example, slit the strip so as to form three double row fin tube sections or one could so slit the strip as to form one four row fin strip and one two row fin strip or any other combination of numbers. Whereas Figures 1 and 2 show an arrangement in which the tubular projections are so designed as to form tubes having an oblong opening so that the tubes are relatively flat, Figure 4 shows an arrangement in which circular tubes would be formed. Rather than duplicating the showing of dies for both types of tube formations, there has been shown in Figure 3 the one set of dies for use in making the round tubes. The same principles are applicable for making the round shaped tubes as for making the flatter tubes.

These tubular projections 16 are formed in a punch press of the general type shown in Figure 3 wherein an upper die member 18 mounted on a conventional plunger 20 moves vertically with respect to the lower die holder

22. The sheet metal strips, such as strip 10, are fed in between the dies and are advanced from left to right. A plate or die holder 24 is drilled to receive and support the forming tools or male dies 26. The lower die member 22 is provided with complementary recessed female dies 28 which are arranged in alignment with the forming tools or dies 26. Spring pressed plungers 30 are arranged as shown and are adapted to lift the strip being formed out of the die recess to permit the strip to be fed forward. An intermediate stripper plate 32 which is perforated to permit sliding movement of the forming tools 26 is provided as shown and serves as a stripper.

The plate 32 is in effect a flat faced plunger or pressure pad which is adapted to cooperate with the flat top of the lower die member 22 to flatten or smooth out the metal strip passing through the forming die. The function of the various dies 26 is to progressively form on and from the strip 10 rows of integral tubular projections transverse to the strip and to accomplish this result without rupturing the strip or materially thinning or weakening the metal beyond the requisite requirements which goes into the tubes. To this end the first of the dies 26

which the strip encounters is adapted to form broad shallow depressions resulting in a recess on the upper side of the sheet metal strip as viewed in Figure 4 and a projection or bulge on the under side thereof, such as the depression 40.

The second of the dies 26 which is encountered by the strip serves to partially reduce and draw in the sides of the strip so as to reduce the width of the strip, as clearly indicated in Figures 1 and 4. The succeeding dies 26 progressively deepen and narrow the depressions or tubular projections 16 as shown in Figures 1 and 4. Each succeeding operation progressively reduces the diameter or the length of the transverse periphery.

The first tool and die 26 cooperate to form a recess on one side of the sheet metal and a bulge on the opposite side. The cross sectional area of this recess, taken in the plane of the sheet metal, is much larger than a cross sectional area taken in the plane of the sheet metal of the ultimate tubular projection. The tools or dies 26 and 28 decrease in transverse cross sectional area progressively, so that each succeeding set of dies is smaller in transverse cross sectional area than the cross sectional area of the preceding set of dies. The length of each succeeding die 26 and the depth of the succeeding die 28 increases, so that the metal of the bulge is gradually reduced in cross sectional area and at the same time gradually elongated. Substantially all of the metal found in the final tubular projection has been derived from the metal in the first bulge that is formed.

In the final operation in forming the tubular projections, the bottom of the cavity is punched out or severed, so as to open up the bottom of the recess or cavity. The side walls of the frustum-conical portions of the recess bear a constant angle with respect to the plane of the sheet metal from the beginning to the next to the last forming operation. In other words the elements generating the successive frustum-conical projections form the same angle with the plane of the sheet metal strip throughout each of the forming stages with possibly the exception of the last forming operation. During the last forming operation, the angle may be changed slightly, so as to properly telescope the tubular projection of one member into the tubular projection of an adjoining member of the heat exchange unit.

One of the big distinctions between dies of the type shown in Figure 3 of the drawing and the type formerly used and shown in my prior Patent No. 1,669,761 is that the sides of the dies 26 and 28 are all arranged at the same angle which preferably is a 5° angle. The angle may be a little more or a little less than 5° providing the angle of all the dies is the same with the possible exception of the last one. By virtue of providing progressive dies 26 and 28 in which the sides of the main forming dies have a 5° angle, the wear on the dies will affect all dies in the same manner and consequently it will not be

necessary to provide shims as the dies wear. The last of the dies 26 to encounter the strip may have an angle slightly less than the 5° angle so as to accurately shape the tubular projection so that the telescoping tube sections will telescope the proper distance and provide a tight joint.

"Frustum-conical," as used herein, is used to designate side walls of the recesses and the bulges or projections as shown in Figure 1 or as shown in Figure 4. In other words, the conical section need not necessarily have a round base. It may have an oblong or elongated base, as shown in Figure 1.

"Tubular projections," as used herein, is used to designate the projections made according to this invention, whether they are round, oblong or some other configuration.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A progressive die for drawing tapered tubular projections from a sheet of material, said die including a progressive series of aligned sets of male and female die members, the male die members being mounted on a common die holder so as to be moved in unison relative to the female die members, each of the male and female die members being of conical form and having the same angle of taper, whereby the impact force of the series is more evenly distributed over the individual die sets with changes in thickness of the sheet material, each succeeding set of dies having a reduced cross sectional area with the same taper and each succeeding set of dies having longer male and female die members than preceding sets, so as to progressively reduce the diameter of the projections and increase the length thereof without changing the angle of the side walls of the projections.

2. The structure of claim 1 wherein an initial die set serves to draw a bulge directly from said sheet and wherein one or more finishing die sets follow said uniformly tapered die sets.

3. The structure of claim 1 wherein said angle of taper is substantially five degrees (5°).
